Inventori

UNITED STATES PATENT OFFICE.

THEODORE HAUSER, OF CHICAGO, ILLINOIS.

SOFA-BED.

SPECIFICATION forming part of Letters Patent No. 767,059, dated August 9, 1904.

Application filed December 4, 1901. Serial No. 84,638. (No model.)

To all whom it may concern:

Be it known that I, THEODORE HAUSER, a citizen of the United States, residing at Chicago, in the county of Cook and State of Illinois, have invented a new and useful Improvement 5 in Sofa-Beds, of which the following is a specification.

My invention relates particularly to a locking device for the swinging leaf of a sofa-bed; 10 and my primary object is to provide a simple automatic lock of this character capable of ready manual release.

The accompanying drawings illustrate my present improvement in connection with a 15 sofa-bed having other features of novelty, which are fully described and claimed in my application of even date, Serial No. 84,639.

In the drawings, Figure 1 represents an end view of a sofa-bed equipped with my improvements; Fig. 2, a broken plan view of the same in the extended or bed form; Figs. 3 and 4, detail views of a caster connection employed, Fig. 4 being taken as indicated at line 4 of Fig. 1; Fig. 5, a broken section taken as indicated at line 5 of Fig. 8 and looking toward the inner side of an end of the sofa-bed, showing the rear leaf of the sofa-bed in a vertical position; Fig. 6, a similar view showing the rear leaf in the horizontal position; Fig. 7, a 30 similar view showing the rear leaf in a depending vertical position; Fig. 8, an enlarged broken section taken as indicated at line 8 of Fig. 1 and looking toward the rear; Fig. 9, a plan sectional view, diagrammatic in its nature, taken as indicated at line 9 of Figs. 1 and 35 8; and Fig. 10, a section taken as indicated at line 10 of Fig. 9 and showing the manner of supporting the lever employed in the locking mechanism.

40 The invention is here illustrated as applied to a sofa-bed of steel construction.

A represents a seat-frame, supported on end standards A', B a rear swinging leaf connected with said seat-frame, and C a front 45 swinging leaf connected with said seat-frame. The leaf C may be swung from a vertical depending position to a horizontal position, as indicated by the dotted lines in Fig. 1, and secured in said position by means of a lock D,

forming the subject-matter of my above-mentioned application. 50

My present invention is confined to a lock E for the leaf B and to an improved caster connection F with which the sofa-bed is equipped. The seat-frame A comprises, preferably, an angle-iron a at each end of the sofa-bed, (one only being shown,) while each standard A' is preferably formed with uprights a' a^2 and a transverse base angle-iron a^3 . The angle-iron a^3 has a downturned wing or flange 60 a^4 and an inturned wing or flange a^5 . At its ends the flange a^5 is cut away, and the projecting ends of the flange a^4 are curved inwardly to afford spring-metal retaining-sockets a^6 for the shanks of the casters. These 65 sockets are of somewhat less diameter than the caster-shank and serve to hold the latter firmly in position after insertion. The end standards A' are joined by angle-irons b , connecting corresponding upright members a' and a^2 , 70 suitable braces b' b^2 being provided.

The locking device E comprises links c , joined by pivots c' to the end members of the leaf B and passing at their lower portions through slots c^2 of the inturned flanges of the 75 upright angle-irons a' , and spring-held locking-bolts d , joined by connections d' with a lever d^2 on a pivot d^3 , said lever being actuated by a cord or wire d^4 , projecting through a perforation in one of the uprights a' and terminating in a ring or handle d^5 . As shown in Fig. 10, the pivot d^3 is supported from the rear angle-iron b by means of a small angle d^6 , connected with the depending wing or flange of the angle-iron b . The pivotal point d^3 is preferably at or near the longitudinal center of the sofa-bed, as may be judged from Fig. 9. The bolts d pass through guides afforded by the downturned ends of U-shaped irons f , Figs. 8 and 9, secured to the horizontal flange of the 80 rear angle-iron b . Spring-coils f' tend normally to thrust said bolts outwardly. The lower ends of the links c , assuming them to be in the position indicated in Fig. 5, are curved forwardly, upwardly, and backwardly and 85 terminate in shoulders g . Said links are provided at their free ends with bolt-receiving perforations g' g^2 , corresponding, respectively,

with the locking positions of Figs. 5 and 6. When the leaf B is depressed, as shown in Fig. 7, the outer ends of the bolts *d* press against the inner sides of the links, but do not lock the links. As shown in Fig. 9 particularly, the flanges of the upright angle-irons *a'*, which are parallel with the ends of the sofa-bed are provided with perforations which receive the extremities of the bolts *d* when the latter are extended. It is usual in sofa-beds of this general type to cover the whole frame, including back, seat, and front leaf, with a spring-held wire-netting adapted to receive a suitable mattress. A portion of such a netting is shown in Fig. 2, 15 where the width of the device when in the form of a bed is shown.

The manner of operation of my improved locking device will readily be understood from the foregoing description. The leaf B may occupy the position of the full lines in Fig. 1, the horizontal position indicated by dotted lines, or the vertical position indicated by dotted lines. In the vertical depending position of the leaf B, as illustrated in Fig. 7, the outer 20 extremities of the bolts *d* simply bear against the inner surfaces of the links *c*. When the leaf B is raised to a horizontal position, the bolts enter the perforations *g'* of the links *c*, thereby locking the leaf in the horizontal position. 25 30 When it is desired to move the leaf from a horizontal position to either the upright standing position of the full lines of Fig. 1 or the vertical depending position of the dotted lines in Fig. 1, this can be done by pulling upon the wire *d'* by means of the ring *d''* and thereupon moving the leaf in the desired direction. When brought to the position of Fig. 1, the bolts enter the perforations *g'* of the links *c*, while the shoulders *g* abut against the front 35 40 surfaces of the inturned flanges of the upright angle-irons *a'*, firmly locking the back-frame against rearward movement. With this construction it is possible to avoid lost motion when the back-frame B is in the standing position. While the lever *d''* is here shown pivoted to swing in a horizontal plane, it will 45 readily be understood that it may be adapted to swing in a vertical plane instead.

Changes in details of construction within 50 the spirit of my invention may be made. Hence no undue limitation is to be understood from the foregoing detailed description.

What I claim as new, and desire to secure by Letters Patent, is—

1. In a sofa-bed, the combination with a 55 suitably-supported seat-frame, an upwardly-extending swinging leaf pivotally connected therewith, a link pivotally connected with said leaf above the pivotal point thereof and having a forwardly, upwardly and rearwardly 60 curved lower end located beneath said seat-frame, a stationary guide, a manually-retracted, yieldingly-held bolt for lockingly engaging said link at a given point, and a stationary shoulder engaging the lower extremity 65 of said link above said bolt.

2. In a sofa-bed, the combination with a 70 suitably-supported seat-frame, and an upwardly-extending swinging leaf pivotally connected therewith and constructed to swing to a vertical depending position, of a link pivoted to said leaf above the pivotal point thereof and having a substantially straight upper portion and forwardly-curved lower end located beneath said seat-frame, said link being provided with two locking-shoulders corresponding, respectively, to the vertical and horizontal positions of said leaf, a stationary guide, and a manually-retracted, yieldingly-held locking-bolt serving to engage the appropriate one of said locking-shoulders, according 75 80 to the position of said leaf.

3. In a sofa-bed of the character described, the combination of end standards having rear upright angle-irons with inturned flanges 85 provided with slots, an upwardly-extending pivoted leaf, links pivotally connected with the ends of said leaf and having forwardly-curved lower ends extending through said slots and provided with locking-shoulders, and manually-retracted spring-held locking-bolts engaging said links.

4. In an article of the character described, the combination with the supports thereof, of horizontally-disposed base members comprising angle-irons each having an inturned flange and a downturned flange, the inturned flange being cut away at its ends and the projecting extremities of the downturned flange curved inwardly to afford a caster-socket.

THEODORE HAUSER.

In presence of—
ALBERT D. BACCI,
W. M. B. DAVIES.
